CENTRIFUGE

Lewis L. Huelsdonk, Downieville, Calif.

Application March 28, 1949, Serial No. 83,959

7 Claims. (Cl. 233—7)

1

This invention is directed to, and it is an object to provide, a novel centrifuge especially designed, but not limited, for use in connection with the processing of ore when in the form of a water pulp.

Another object of the invention is to provide a centrifuge which is adapted to function effectively to condense and control pulp densities; to dewater or deslime pulps; to classify or thicken pulps; and to act as a centrifugal concentrator without extraneous media.

An additional object of the invention is to provide a centrifuge which is operative to function with a continuous discharge; this being especially advantageous in the processing of ore where large quantities must be handled rapidly to attain economy and profitable returns.

A further object of the invention is to provide a centrifuge which is characterized by mechanical simplicity, being designed for ease and economy of manufacture, and for ready manual control over all its functions during operation.

It is also an object of the invention to provide a centrifuge which includes novel differential drive mechanism for the rotary cone and relatively rotatable feed spiral or spiral conveyor therein.

A separate object of the invention is to provide a centrifuge which includes novel manually controlled mechanisms to accomplish adjustment of the overflow spouts and middlings spouts while the same travel with the rotary cone.

Other advantages are its versatility to different operations without many adapters or accessories; its high efficiency and low maintenance costs; and its high capacity relative to occupied floor space.

A still further object of the invention is to provide a practical and reliable centrifuge, and one which will be exceedingly effective for the purpose for which it is designed.

These objects are accomplished by means of such structure and relative arrangement of parts as will fully appear by a perusal of the following specification and claims.

In the drawings:

Fig. 1 is a side elevation of the centrifuge.

Fig. 2 is a mainly sectional elevation of the same.

Fig. 3 is an enlarged sectional elevation of the rotary cone showing the cooperating working parts therein.

Fig. 4 is a sectional plan on line 4—4 of Fig. 1.

Referring now more particularly to the characters of reference on the drawings, the centrifuge

2

is comprised of an upstanding cylindrical housing 1 of substantial diameter and height, being supported above the floor by relatively short, circumferentially spaced legs 2.

5 The cylindrical housing 1 includes a bottom plate 3, and is normally closed at its upper end by a removable top plate 4.

An inner cylinder 5 and an intermediate cylinder 6 are disposed in the cylindrical housing 1 in concentric spaced-apart relation, and with the intermediate cylinder 6 spaced from said housing 1, whereby to form a pair of circumferential passages; the inner passage being indicated at 7 and the outer passage at 8. A discharge spout 9 leads from the lower end of the inner passage 7 to a discharge point exteriorly of the cylindrical housing 1, while another discharge spout 10 leads from the bottom of the outer passage 8 to a discharge point exteriorly of the cylindrical housing 1, but on the opposite side thereof.

The cylinders 5 and 6 are of considerably lesser height than the housing 1 whereby to form an upper chamber 11 in the latter above an anti-splash flange 12 mounted in said housing. An 15 upstanding rotary cone 13 is disposed in the housing 1 within the inner cylinder 5, being of only slightly greater height; such rotary cone including, at its lower end, a depending tubular discharge spout 14 carried in a bearing 15 on the bottom plate 3. The rotary cone 13 includes a head plate 16 having a central opening defined by a bearing collar 17.

A vertical feed tube 18 extends centrally through the top plate 4 and is carried by a bearing 19 thereon; such feed tube depending from the bearing 19, through the upper chamber 11, thence through the bearing collar 17 with a close running fit, and then depending into the rotary cone 13 to a lower end termination some distance 40 above the discharge spout 14.

At its upper end the feed tube 18 includes a feed hopper 20 through which the ore pulp is fed into the centrifuge.

Within the rotary cone 13 the feed tube 18 is 45 fitted with a spiral conveyor 21 which has a relatively close running fit within said rotary cone 13; the spiral conveyor extending substantially from top to bottom of said cone, being relatively narrow in width and adapted to turn in the direction indicated by the arrow in Fig. 3.

In addition, the feed tube 18 and spiral conveyor 21 may be fitted, for certain operations, with fins 22 or a counter-spiral agitator 23 (or both); these parts being indicated in dotted lines 55 in Fig. 3.

A vertical adjustment rod 24 extends from a point above the housing 1 downwardly through the feed tube 18 and tubular discharge spout 14 axially thereof; said adjustment rod terminating at its lower end in a taper plug valve 25 which works in cooperation with a seat 26 formed on the lower end of said discharge spout 14. The rod 24 is vertically shiftable, whereby to accomplish adjustment of the plug valve 25, by means of a hand lever 27 pivotally mounted above the housing 1 on a bracket 28; one end of such hand lever being coupled by a ball thrust swivel 29 to the rod 24. The hand lever 27 is normally but releasably held in a latched position by means including a notched quadrant 30.

The rod 24 is maintained in guided relation in the feed tube 18 by spiders 31 which are slidably splined, as at 32, in connection with the inner wall of said feed tube.

The adjustment rod 24, in addition to serving as the means to set or regulate the plug valve 25, also serves as a means to feed water into the ore pulp in the centrifuge, and this is accomplished as follows:

The rod 24 is hollow, and at its upper end includes a hopper 33, into which water is adapted to be fed. For pressure application the hopper 33 is omitted and a water pressure conduit is connected to the rod 24 by a swivel fitting (not shown).

Below the lower end of the feed tube 18 the tubular rod 24 is fitted with laterally extending water jets or nozzles 34 disposed in vertically spaced relation and mounted to discharge in various directions for the purpose of agitating the mass or bed of pulp in the lower portion of the rotary cone 13. Additionally, the rod 24 is fitted, within the discharge spout, with lifter paddles 35 in circumferentially and vertically spaced relation.

If desired, compressed air may be introduced through the rod 24 and nozzles 34 for the purpose of agitation of the material in the rotary cone.

The rotary cone 13 and feed tube 18 are driven in the same direction, but at selectively variable relative speeds, by means of the following drive mechanism:

A vertical shaft motor 36 is mounted on the outside of the housing 1 adjacent the top thereof, and such motor is connected in driving relation by an endless belt and pulley unit 37 to the case 38 of a differential, indicated at 39. The case 38 is fixed to the head plate 16 of the rotary cone 13. With this arrangement said rotary cone is driven by the motor 36 at a constant speed.

Within the case 38 the differential 39 includes one end gear 40 affixed to the feed tube 18, and the other end gear 41 having an exposed worm gear 42 driven by a worm 43; the latter being actuated by an endless belt and pulley unit 44 powered by a variable speed motor 45 on the top plate 4. The end gears 40 and 41 of the differential 39 are coupled together, within the case 38, by spider gears 46.

It will be recognized that when the worm gear 42 is stationary, the differential 39 will impart rotation to the feed tube 18 and its spiral conveyor 21 at the same speed, and in the same direction, as the rotary cone 13. However, upon powered rotation of said worm gear 42 by the driving means therefor, including motor 45, a differential speed results between the rotary cone 13 and the feed tube 18. In this manner the operator can effect a nicety of relative speed

control between the rotary cone 13 and the feed tube 18 which carries the spiral conveyor 21. In other words, the speed of said feed tube 18 can be varied, selectively, by the simple expedient of altering the speed of motor 45 by any conventional instrumentality.

Closely adjacent the top thereof, and in circumferentially spaced relation, the rotary cone 13 is fitted with a plurality of overflow spouts 47 which discharge, exteriorly of the cone 13, into the inner circumferential passages 7; the latter feeding to the discharge spouts 9, as previously described.

The overflow spouts 47 each include a valve 15 48 having an upstanding stem 49 fitted, at its upper end above the head plate 16, with an adjustment wheel 50. Each valve 48 includes a sprocket 51 below the corresponding adjustment wheel 50 and all the said sprockets are interconnected by an endless chain 52. Thus, with turning of one adjustment wheel 50, the others are simultaneously and correspondingly turned.

A plurality of circumferentially spaced middling spouts 53 extend out of the rotary cone 13 adjacent the top thereof, with the outer ends of said spouts 53 in position to discharge into the outer circumferential passage 8 which feeds to the discharge spout 10, as previously described.

The middling spouts 53 include a horizontal portion which is journaled, as at 54, in connection with the rotary cone 13; the inner or intake end of each spout 53 being downturned or generally L-shaped, as at 55, for the purpose of being set to selective pick-up levels by rotation of the corresponding spout 53.

Each spout 53 is adapted to be rotatably adjusted by means comprising a worm gear 56 fitted on each spout outside its journal 54, each journal being attached by a bracket 57 to the head plate 16.

A worm 58 on a vertical stub shaft 59 meshes with each worm gear 56, and above the head plate 16 each such shaft 59 includes an adjustment wheel 60. A sprocket 61 is secured on each shaft 59 below the adjustment wheel 60 and said sprockets are coupled together by an endless chain 62 so that with turning of one adjustment wheel 60 all are turned in the same direction and to a corresponding extent, whereby to accomplish like adjustment of the middling spouts 53.

The adjustment wheels 50 travel in one circumferential path, while the adjustment wheels 60 travel in another circumferential path, and the following mechanisms are employed to cause selective adjustment of the wheels 50 or 60, while the rotary cone 13 is traveling.

At one point in their path of circumferential travel, the adjustment wheels 50 pass between a pair of arcuate shoes, the inner shoe being indicated at 63 and the outer shoe at 64; said shoes being connected by an upstanding yoke 65 and suspended from a bracket assembly 66 for lateral shifting motion. This lateral shifting motion of the shoes 63 and 64, as a unit, is accomplished by a toggle linkage 67 actuated by a control rod 68 which projects out of the housing 1 to termination in a handle 69. By shifting the control rod 68 in one direction or the other, the toggle linkage 67 causes either the inner shoe 63 or outer shoe 64 to shift in a direction to frictionally engage the adjustment wheels 50 as they pass between the shoes. This results in turning of the adjustment wheels 50 in one direction or the other as working conditions may require.

The wheels 60 for the middling spouts 53 are

regulated by a similar mechanism which includes a shoe unit having an inner shoe 70 and an outer shoe 71 connected by a yoke 72; the shoe unit being suspended from a bracket assembly 13 actuated by a toggle linkage 14. A control rod 75 leads out of the housing 1 from the toggle linkage 14 and said rod terminates outside the housing in a handle 76. By shifting the control rod 75 in one direction or the other, either the inner shoe 70 or outer shoe 71 cooperatively engages the adjustment wheels 60 to rotate the middling spouts 53 so as to either raise or lower the in-takes 55.

It will be recognized, at this point, that the operator, by the simple manipulation of the hand lever 21 and the handles 69 and 76, together with the variable speed control for the motor 45, can effectively control the centrifuge action of the machine, and the discharge therefrom through the overflow spouts 47, middling spouts 53, and lower end discharge spout 14.

When the centrifuge is in operation, ore pulp is fed into the hopper 20, whence it delivers through the feed tube 18 into the rotary cone 13 for processing, which processing includes particle segregation under the centrifugal force and settling action of the apparatus. The particles which are less susceptible to the settling action are carried upward to the middling spouts 53 and overflow spouts 47. The relative speeds of rotation, intensity of agitation, gravity of feed, and density of the medium are determining factors for the overflow product, while these factors plus the adjustment position of the middling spouts govern the middling product.

Particles most susceptible to the action are forced to the walls of the cone where they are in turn carried down to the discharge spout 14 by the spiral conveyor 21, the relative speed of which is controlled by the variable speed motor 45 in the manner previously described.

The described machine functions effectively as a continuous discharge centrifuge, and may be used to condense and control pulp densities; to dewater and deslime pulp; to classify and thicken pulp; and to act as a centrifugal concentrator whereby heavies from the pulped ore becomes the medium for separation. As a centrifugal concentrator the machine is operative beyond the point of effectiveness of heavy media and sink float processes; i. e. on "minus $\frac{1}{4}$ " pulp.

Where desliming is necessary prior to concentration, one of the described centrifuges may be used in preparing the feed for another.

When used as a concentrator the rotary cone 13 is revolved at a speed which moves the heavies outward. The spiral conveyor, with the special fins 22 or agitators 23 if necessary, is set to revolve at a speed so different from that of the rotary cone that a near balance exists between agitation and centrifugal force, allowing the heavier particles to penetrate the more or less heterogeneous mass to a point where the spiral carries them down the wall of the rotary cone 13 to a bed below the feed tube 18 and above the discharge spout 14. The lifter paddles 35 and the water jets 34 help keep the concentrated mass mobile and the interstices between the particles filled with water as a lubricant; thus allowing the lighter particles to move upward through the high density bed where they can join the centrifugally influenced mass of agitated pulp for further segregation and eventual separation. The uppermost water jets 34 which are dual, and which project some distance laterally from the

rod 24, act as mechanical agitators as well as water injecting nozzles.

The density of the mass, which must be maintained within specified limits in the rotary cone 13, is controlled by:

(1) Adjustment of the taper plug 25 to allow a dense mass of mineral to build up in the rotary cone, or to drain it to a point where a small concentrate bed is maintained, selectively;

(2) By regulating the relative speeds of rotation, as previously described, to control the severity of agitation; and

(3) By injecting more or less water into the mass through the jets 34.

Tailings can be taken from both the overflow spouts 47 and middling spouts 53, or middlings can be drawn for regrind where ore maintains locked values in an "in-between" or "balanced" specific gravity pulp.

It will be recognized from the foregoing that the described centrifuge is of high adaptability to the ore processing operations contemplated herein; the adjustments being simple and readily accomplished, and the machine being extremely effective and accurate in its operation.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A centrifuge, for processing ore pulp, comprising a support, an inverted cone rotatably mounted on the support, a feed tube depending axially into the cone and rotatably mounted on the support, means to rotate the cone and feed tube, a pulp agitator on the feed tube in the cone, a valve-controlled discharge spout on the lower end of the cone, the feed tube terminating in the cone above said lower end of the latter, a hollow control rod depending through the feed tube and discharge spout, water discharge nozzles projecting from the rod below the tube, the valve of the discharge spout being mounted on and vertically adjustable by the rod, and means on the support vertically adjustably suspending the rod above the cone.

2. A centrifuge, for processing ore pulp, comprising a support, an inverted cone rotatably mounted on the support, a feed tube depending axially into the cone and rotatably mounted on the support, a pulp working structure on the feed tube in the cone, a valve-controlled discharge spout on the lower end of the cone, the feed tube terminating in the cone above said lower end of the latter, a control rod depending through the feed tube and discharge spout, the valve of the latter being mounted on and vertically adjustable by the rod, means on the support vertically adjustably suspending the rod above the cone, and power means connected to the cone and feed tube to rotate the same; the control rod being hollow, lateral jets on the hollow rod below the feed tube, and means to deliver a fluid to said rod.

3. A device as in claim 2 in which the outlet spout includes a vertically depending tube, the

rod extending axially therethrough, and lifter paddles on the rod in said depending tube.

4. A device, as in claim 3, in which the control rod is mounted for rotation with the feed tube.

5. A centrifuge for processing ore pulp, comprising a support, an inverted cone rotatably mounted on the support, a feed tube depending axially into the cone and rotatably mounted on the support, means to rotate the cone and tube at selected and relatively different speeds, the feed tube terminating at its lower end above the corresponding end of the cone, an adjustable discharge spout at the lower end of the cone including a vertically adjustable valve, a hollow control rod vertically adjustably suspended from the support and depending through the feed tube and cone to connection with said valve, water discharge nozzles projecting from the rod below the feed tube, a spiral conveyor on the feed tube in the cone, and other adjustable spouts leading from the cone adjacent its upper end.

6. A centrifuge for processing ore pulp, comprising a support, an inverted cone rotatably mounted on the support, a feed tube depending axially into the cone and rotatably mounted on the support, the feed tube terminating at its lower end above the corresponding end of the cone, an adjustable discharge spout at the lower end of the cone including a vertically adjustable valve, a control rod vertically adjustably suspended from the support and depending through the feed tube and cone to connection with said valve, a spiral conveyor on the feed tube in the cone, other adjustable spouts leading from the cone adjacent its upper end, and power means connected to the cone and feed tube to rotate the same at selectively relatively differential speeds; the control rod being hollow and mounted to ro-

tate with the feed tube, jets on the hollow rod below the feed tube, and means to feed a fluid to said hollow rod.

7. In a centrifuge which includes a rotary receptacle, a plurality of spouts leading from the receptacle adjacent its upper end, each such spout including an adjustment wheel exposed above the receptacle, means operative to rotate the receptacle, connections coupling all of said adjustment wheels for turning in unison and to the same extent, and means operative to so turn the adjustment wheels while the receptacle is rotating; the adjustment wheels being disposed to travel in the same circumferential path, and said last named means including a friction shoe unit having shoes on opposite sides of said path, and hand means operative to shift the shoe unit in or out to cause one shoe or the other to engage and turn said wheels as the same pass through the shoe unit.
